LATCH MECHANISM

Charles S. Forshey, Caldwell, Ohio

Application September 23, 1957, Serial No. 685,630

7 Claims. (Cl. 292—216)

This invention relates to latch mechanisms for cabinets or the like and particularly to a novel latch mechanism which can be readily opened by adults but which cannot be opened by small children. In general, the latch mechanism of the present invention includes a pair of latch members that are mounted within the frame of the cabinet with one of the members being secured to the frame and the other of the members being secured to the door. The mechanism further includes a pair of actuators which are pivotally mounted within the cabinet and which include handle portions which extend through the side wall of the cabinet so as to be accessible from the exterior thereof. The handle portions of the actuators are partially surrounded by a shield which includes an opening that permits limited access to the handle portions. The latch means within the cabinet are disengaged to permit opening of the door when the two handle portions on the actuators are pressed one toward the other. In order to actuate the handle portions it is necessary for one person to insert his thumb and finger into the above mentioned opening in the shield and to further squeeze the handle portions one toward the other whereby the actuators release the latch means. In the event, however, that a child should attempt to actuate the handle portions the child is unable to accomplish this manipulation since his fingers are too short to extend far enough into the opening to depress the handle portions, moreover, the child's hands are too large to enter the opening so that it is impossible for the child to actuate the shielded handle portions of the actuators. It is therefore an object of the present invention to provide a novel latch mechanism that be readily operated by an adult but which cannot be operated by small children.

Further objects and advantages of the present invention will be apparent from the following description, reference being had to the accompanying drawings wherein preferred forms of embodiments of the invention are clearly shown.

In the drawings:

Figure 1 is a partial perspective view of the interior of a cabinet showing the latch mechanism of the present invention illustrated therein;

Figure 2 is an elevational view partially in section of a portion of the mechanism of Figure 1 with the section being taken along the line 2—2 of Figure 1;

Figure 3 is a plan view of the cabinet and mechanism of Figure 1;

Figure 4 is an elevational view showing the handle portions and shield comprising a portion of the mechanism of the preceding figures, the view being taken along the line 4—4 of Figure 3.

Referring in detail to the drawing Figures 1 and 3 illustrate a portion of a cabinet indicated generally at 20 and including a side wall 21, a back wall 22, and a shelf 23. A door 25, Figure 2, is hinged to the cabinet frame at 26 and a stationary latch portion 27 including a vertical latch pin 28 is mounted at the edge of the door

2

25. A rotary latch element 30 is rotatably mounted on shelf 23 by means of a bracket 31 and bearing pin 32. Rotary latch element 30 is provided with a socket 34 that latches with vertical pin 28 when the latch members are in the configuration illustrated in Figure 3.

A pair of levers or actuators 36 and 37 are pivotally mounted to side wall 21 at pivot 38. The front end of actuator 36 includes a latch element 40 and similarly the front end of actuator 37 includes a second latch element 41. A rod 43 is pivotally mounted to rotary latch 30 at pivot 44 whereby rotation of rotary latch 30 extends and retracts rod 43 relative to latch elements 40 and 41 on actuators 36 and 37 respectively. A third latch element 46 is carried on the end of rod 43 and positioned so that when rotary latch member 30 is in closed position illustrated in Figure 3 the rod 43 and the third latch element 46 carried thereon is extended to the right whereby compression spring 47 must latch elements 40 and 41 toward one another and into latched engagement with latch element 46 on rod 43.

The rear ends of actuators 36 and 37 include handle portions 49 and 50 which extend through slot 51 to the exterior of the cabinet. A shield indicated generally at 53 is mounted to the outer surface of side wall 21 and 25 surrounds handle portions 49 and 50. An opening 55 in the front of shield 53 provides limited access for the actuation of handle portions 49 and 50. An obstruction 56 is mounted within shield 53 centrally of opening 55 and such obstruction divides the opening into an upper 30 opening portion 57 and a lower opening portion 58, Figure 4. To press the handle portions 49 and 50 one toward the other, it is only necessary that a person insert his thumb into opening portion 57 above handle portion 49 and his finger into lower opening portion 58 below handle portion 50. The handle portions 49 and 50 are next squeezed together whereby latch members 40 and 41, Figure 1, are caused to move apart whereby latch portions 40 and 41 on actuators 36 and 37, respectively, release latch portion 46 on the end of the rod 43. Door 25 can then be pulled open since rotary latch 30 is free to rotate once the latch elements 40 and 41 release the latch element 46.

It should be pointed out that the thumb access space provided by upper opening portion 57 and the finger access space provided by lower opening portion 58 are made small enough to prevent a small child from inserting his two hands into the opening portions. Moreover, the distance between upper handle portion 49 and lower handle portion 50 is too great for a child to span with his thumb and finger. Since it is necessary to move both of the handle portions 49 and 50, in order to release latch element 46, it will be understood that it is virtually impossible for a small child to actuate the latch mechanism.

55 In operation, when both the handle portions 49 and 50 are moved one toward the other, actuators 36 and 37 are moved together in the back and spread in the front whereby latch elements 40 and 41 release latch element 46 and permit rotary latch member 30 to rotate whereby stationary latch member 27 is released and door 25 can be opened. When door 25 is closed pin 28 enters slot 34 and rotary latch member 30 rotates to the closed position illustrated in Figure 3. As this occurs latch members 40 and 41 are moved apart and latch member 46 moves to the right into a position of locked engagement with latch elements 40 and 41.

While the forms of embodiments of the present invention as herein disclosed constitute preferred forms, it is to be understood that other forms might be adopted, all coming within the scope of the claims which follow.

70 I claim:

1. A door latch mechanism for use with a cabinet or

the like having a frame means and a door means hinged to said frame means, said latch mechanism comprising, in combination, a first latch member carried by one of said means; a second latch member carried by the other of said means, one of said latch members being moveable between a latched position wherein said door means is maintained closed and a released position wherein said door means can open, said two latch members being inaccessible from the exterior of said cabinet frame means; a pair of levers pivoted to said frame, each of said levers including a latch element inaccessible from the exterior of said cabinet frame means and a handle portion accessible from the exterior of said cabinet means; a rod having one end secured to said moveable latch member and the other end provided with a third latch element engageable with said latch elements of said levers; and means urging said latch elements into engagement with one another.

2. A door latch mechanism for use with a cabinet or the like having a frame means and a door means hinged to said frame means, said latch mechanism comprising, in combination, a first latch member carried by one of said means; a second latch member carried by the other of said means, one of said latch members being moveable between a latched position wherein said door means is maintained closed and a released position wherein said door means can open, said two latch members being inaccessible from the exterior of said cabinet frame means; a pair of levers pivoted to said frame, each of said levers including a latch element inaccessible from the exterior of said cabinet frame means and a handle portion accessible from the exterior of said cabinet means; a rod having one end secured to said moveable latch member and the other end provided with a third latch element engageable with said latch elements of said levers; means urging said latch elements into engagement with one another; and housing means for said handle portions, said housing means including an opening providing restricted access to said levers.

3. A door latch mechanism for use with a cabinet or the like having a frame means and a door means hinged to said frame means, said latch mechanism comprising, in combination, a first latch member carried by one of said means; a second latch member carried by the other of said means, one of said latch members being moveable between a latched position wherein said door means is maintained closed and a released position wherein said door means can open, said two latch members being inaccessible from the exterior of said cabinet frame means; a first lever pivoted to said frame and including a latch element inaccessible from the exterior of said cabinet frame means and a handle portion accessible from the exterior of said cabinet means; a second lever pivoted to said frame and including a latch element inaccessible from the exterior of said cabinet frame means and a handle portion accessible from the exterior of said cabinet means, said two levers being coextensive with the handle portion and latch elements in spaced relationship; a rod having one end secured to said moveable latch member and the other end including a third latch element disposed between said first and second latch elements; and means urging said latch elements into engagement with one another.

4. A door latch mechanism for use with a cabinet or the like having a frame means and a door means hinged to said frame means, said latch mechanism comprising, in combination, a first latch member carried by one of said means; a second latch member carried by the other of said means, one of said latch members being moveable between a latched position wherein said door means

is maintained closed and a released position wherein said door means can open, said two latch members being inaccessible from the exterior of said cabinet frame means; a pair of levers pivoted to said frame, each of said levers including a latch element inaccessible from the exterior of said cabinet frame means and a handle portion accessible from the exterior of said cabinet means; a rod having one end secured to said moveable latch member and the other end provided with a third latch element engageable with said latch elements of said levers; means urging said latch elements into engagement with one another; and housing means for said handle portions, said housing means including an opening providing restricted access to said levers.

5. A door latch mechanism for use with a cabinet or the like having a frame means and a door means hinged to said frame means, said latch mechanism comprising, in combination, means inaccessible from the exterior of said cabinet frame means and forming a latch between said door means and said frame means; a pair of moveable actuators accessible from the exterior of said cabinet means spaced one from another outside said cabinet; and means inaccessible from the exterior of said cabinet frame means for operatively connecting said actuators with said latch means and including a first latch shoulder releasably engageable with one of said actuators and a second latch shoulder releasably engageable with the other of said actuators.

6. A door latch mechanism for use with a cabinet or the like having a frame means and a door means hinged to said frame means, said latch mechanism comprising, in combination, means inaccessible from the exterior of said cabinet frame means and forming a latch between said door means and said frame means; a pair of moveable actuators accessible from the exterior of said cabinet means spaced one from another outside said cabinet; means inaccessible from the exterior of said cabinet frame means and connected to said latch means and releasably engaged by said actuators; and shield means comprising a first wall adjacent one of said actuators and a second wall adjacent the other of said actuators, the spaces between each actuator and its respective wall being slightly greater than the diameter of a finger.

7. A door latch mechanism for use with a cabinet or the like having a frame means and a door means hinged to said frame means, said latch mechanism comprising, in combination, means inaccessible from the exterior of said cabinet frame means and forming a latch between said door means and said frame means; a pair of moveable actuators accessible from the exterior of said cabinet means spaced one from another outside said cabinet; means inaccessible from the exterior of said cabinet frame means and operatively connecting said actuators with said latch means and including a first latch shoulder releasably engageable with one of said actuators and a second latch shoulder releasably engageable with the other of said actuators; and shield means comprising a first wall adjacent one of said actuators and a second wall adjacent the other of said actuators, the spaces between each actuator and its respective wall being slightly greater than the diameter of a finger.
